(57) **CLAIM**

I claim the ornamental design for a clasp, as shown and described.

DESCRIPTION

FIG. 1 is a front, right perspective view of the clasp in a closed condition with its post engaged;

FIG. 2 is a front, right perspective view thereof closed with the post disengaged;

FIG. 3 is a front, right elevational view thereof in an open condition;

FIG. 4 is a front elevational view thereof;

FIG. 5 is a right side elevational view thereof;

FIG. 6 is rear elevational view thereof;

FIG. 7 is a left side elevational view thereof;

FIG. 8 is a top plan view thereof; and,

FIG. 9 is a bottom plan view thereof.

The broken lines in FIGS. 1-4 and 6 represent conventional stitching.
